I. W. VAN GUNten

AUTOMOBILE RADIATOR DECORATION

Filed Sept. 19, 1927

Inventor

IRVIN W. VAN GUNten

By

Geo Kirk

Attorney

UNITED STATES PATENT OFFICE.

IRVIN W. VAN GUNten, OF TOLEDO, OHIO.

DESIGN FOR AN AUTOMOBILE RADIATOR DECORATION.

Application filed September 19, 1927. Serial No. 23,458. Term of patent 3½ years.

To all whom it may concern:

Be it known that I, IRVIN W. VAN GUNten, a citizen of the United States of America, residing at Toledo, Lucas County, Ohio, have invented a new, original, and ornamental Design for an Automobile Radiator Decoration, of which the following is a specification, reference being had to the accompanying drawing, forming a part thereof.

Fig. 1 is a front elevation of the decoration; and

Fig. 2 is a side elevation of the decoration.

I claim:

The ornamental design for an automobile radiator decoration as shown.

IRVIN W. VAN GUNten.
